UNITED STATES PATENT OFFICE.

WILLIAM M. GROSVENOR, OF RIDGEWOOD, NEW JERSEY.

HANDLING AND TREATING COMBUSTIBLE GASES AND VAPORS.

1,143,623.

Specification of Letters Patent. Patented June 22, 1915.

Application filed June 27, 1911. Serial No. 635,684.

To all whom it may concern:

Be it known that I, WILLIAM M. GROSVENOR, a citizen of the United States, and a resident of Ridgewood, county of Bergen, 5 and State of New Jersey, have invented certain new and useful Improvements in Handling and Treating Combustible Gases and Vapors, of which the following is a specification.

10 My invention relates to improvements in handling and treating combustible gases and vapors, and more particularly to the handling of combustible vapors evolved in the drying of various materials, such as the 15 removal and recovery of solvents.

Two forms of apparatus are shown in the accompanying drawings adapted to carry out my improved method or process.

In the drawings, Figure 1 is a transverse 20 vertical section through an apparatus adapted for treating celluloid and the like taken on the line C—C of Fig. 2. Fig. 2 is a horizontal section of the same taken on the line A—A of Fig. 1. Fig. 3 is another horizontal 25 section of the same taken on the line B—B of Fig. 1. Fig. 4 is a vertical section through an apparatus adapted for the treating of artificial leather, taken on the line D—D of Fig. 5. Fig. 5 is a section through the same 30 taken on the line E—E of Fig. 4. Fig. 6 is a section through the same taken on the line F—F of Fig. 5.

The object of my invention is to provide a method by which such vapors may be 35 safely confined in such quantities as is usual in drying chambers, and may be economically condensed under conditions which will entirely eliminate or reduce to a minimum the liability to explosion, due to the mixture 40 of air with the gases and vapors. These mixtures of air and gases or solvent vapors are not explosive when extremely impoverished in combustible vapor or gases, nor are they explosive if the mixture be made so 45 rich in combustible vapor or gases that there is insufficient oxygen for the propagation of the explosive wave.

Further objects, features and advantages 50 will more clearly appear from the detailed description given below.

I find that in the drying of many materials such as celluloid and the like, it is possible to remove the greater portion of the

solvents in an atmosphere so saturated as to be non-explosive, even at the elevated temperatures required to evaporate the solvents into a highly saturated atmosphere or surrounding medium. In this case however, it is found that the solvent can generally not be removed with sufficient completeness to 60 produce a product which will be safe and permanent in storage, and which will not give off enough vapor to render disagreeable or dangerous the atmosphere of the room where quantities are stored. I find 65 however, that if such materials be transferred from this saturated atmosphere to one where very impoverished solvent vapor conditions are maintained, the material will no longer give off sufficient vapors to render 70 the atmosphere in its immediate neighborhood dangerous, and that the treatment of the material may be safely continued in the impoverished drying medium, as by more active condensation at a lower temperature. 75

From the above it will be clear that I provide an improved method for handling such vapors, and drying such materials, which consists in first, maintaining conditions which insure an excessive richness of the 80 drying atmosphere, and thereafter continuing the treatment under conditions which insure excessive impoverishment of the combustible vapors in the drying atmosphere. For instance, it has been determined that 85 mixtures of ethyl alcohol and air containing less than 3.95% alcohol or more than 13.65% are not explosive; that mixtures of air and ether containing less than 2.75% or more than 7.7% are not explosive; that 90 benzol vapors containing less than 2.65% and more than 6.5%, or benzin containing less than 2.4% and more than 4.9%, or methyl alcohol containing less than 7.8% and more than 18%, and acetone containing 95 less than 2.7% and more than about 15% are not explosive under ordinary conditions.

As an example, in the removing of solvents from celluloid according to my improvements, I carry out the treatment in 100 two successive stages. During the first stage I provide the necessary physical and mechanical treatment of any well known character, to liberate the vapors of the solvents, acetone and methyl alcohol, and adjust their 105 rate of removal either by adjusting the

amount of condensation or by adjusting the amount of air admitted, or otherwise, in such a manner that the atmosphere containing the wood alcohol and acetone is maintained in a condition in which it has preferably more than 20% of the mixed vapors of acetone and wood alcohol. Under these conditions I am enabled to remove all the necessary liquid from the material to produce a plastic body ready for pressing and forming. I then subject the material to the further usual mechanical treatment and handling, and to a drying medium adjusted to contain not more than 5% of the mixed vapors of acetone and alcohol, until the volatile liquids are removed to a sufficient extent to permit any further treatment of the plastic material as may be desired, to be carried out with safety.

Referring to Figs. 1, 2 and 3 illustrating a machine for the treatment of celluloid, 49 and 49' represent two chambers one above the other provided with side walls 50 and 50'. The chambers are provided with end walls 52, 52' and 53, 53', bottoms 54 and 54' provided with trap-doors 55 and 55', and top walls 56, 56' each of which is provided with an extension chamber 57, 57', the former serving as a closed connecting passage between the two chambers, and the latter as an inlet hopper for the entire apparatus. Both of the chambers 49 and 49' are provided with partitions 58 and 58' dividing off the ends to form condenser chambers 60, 60' connected with the body of the main chambers at the top and bottom. The condenser chambers contain condensing pipes 61, 61' provided below with troughs 62, 62' to catch the condensed liquid which is carried away by pipes 63, 63'. Fans 65, 65' circulate the gases actively in the drying-chambers proper. In each of the latter chambers is located a pair of sheeting rolls 66, 59 and 66', 59' of any well-known type, their shafts extending out through one side to the usual driving gears, not shown. Instead of being slit and stripped from the rollers by a hand-knife, I provide a beam-knife 67, 67' for each pair of rollers actuated by the spring-thrust rods 68, 68' and levers 69, 69'. Instead of the usual catch-boxes below the rollers there are provided two aprons, a return-apron 70 and 70' and a collection apron. The return-apron consists of a strong broad belt always trailing in the direction of the adjacent rollers 66, 66' over three guide rollers 71, 72 and 73, and 71', 72' and 73', two of which, 71, 72, 71' and 72' are rigidly set in an angle-frame 74, 74', while the roller 73, 73' is attached thereto by spring take-up bearings 75, 75'. The frame 74, 74' is rigidly attached to the worm gear 76, 76' and actuated by shaft 77, 77' and hand-wheel 78,

78' so that it may be swung back to the left 65 about the shaft of roller 71, 71' as an axis to permit free movement forward of the collection-apron 79, 79'. This runs on the rollers 80, 80' and 81, 81', the latter being actuated when desired by gear 82, 82' sliding 70 on the shaft 83, 83' but turning with it when rotated by the hand-wheel 84, 84'. The whole conveyer is supported on a traveling carriage 85, 85' having wheels 86, 86' running on track 87, 87' to advance the conveyer into position under rollers 66, 66', or to return it to the position shown in accordance with the movement of rack 88, 88' attached to the carriage and actuated by pinion 89, 89', which in turn is actuated by beveled gear 90, 90' turned by the shaft 91, 91' and hand-wheel 92, 92'. The distance between the rollers 66, 66' and 59, 59' is regulated by screw take-up bearings 93, 93' actuated simultaneously by a pair of beveled 80 gears 94, 94' and cross-shafts 95 and 95' driven by beveled gears 96, 96' and hand-wheel 97, 97'.

The celluloid cake is placed in the hopper 57', falling down between the rollers 66' 90 and 59' by which it is first broken up, the knife 67' being in the position shown, throws the fragments on the conveyer 70' by which they are continually returned over the top of roller 66' and again passed 95 between the rollers. The rollers are then brought slightly nearer together and a blanket of celluloid gradually collects on and adheres to the roller 66'. After the mass has all accumulated on this roller the 100 return conveyer is no longer needed and is swung back to the left by the operation of the hand-wheel 78'. The blanket is then cut from the roller 66' by throwing the knife 67' over against it by operation of the 105 lever 69' and at the same time the conveyer 79' is advanced by operation of the hand-wheel 92' so that as the blanket is cut and falls from the roller 66' it is caught by the conveyer 79'. When about one-half the 110 blanket has been laid on this advancing conveyer the movement of carriage 85' is reversed so that the blanket is folded upon itself as the carriage returns to the position shown. The return conveyer 70' may now 115 be swung into the position shown, the knife 67' returned to the position shown, and the blanket of celluloid returned to the rolls by turning hand-wheel 78', causing the collection-apron to travel forward and deliver the 120 folded blanket to the return conveyer 70' which carries it up until seized between the conveyer and the roll 66' when it is forced between the two, and strikes the guide-plate 98' by which it is turned over and pushes 125 in the pivoted side of the hopper and goes down again between the rolls.

When once more formed upon the roller

66' the celluloid blanket is sheeted by moving the rollers very close together, swinging back the return conveyer, advancing the collection-apron to the extreme left, and, 5 throwing the knife over against the roll 66' the thin sheet of celluloid is cut from the roller 66 and drops downwardly, and is collected upon the apron 79' in a number of folds by moving the carriage 85' back and forth. When the blanket is all piled upon the apron 79' the thin sheet may be returned again to the roll and the operation repeated as many times as desired, to thoroughly work and mix the goods, removing only such 10 portion of the solvent as is necessary to regulate its working and provide an extremely rich and, therefore, non-explosive atmosphere of solvent vapor in the chamber. The mass may then be dropped through the 15 spring trap-doors 55' into the lower chamber where the same mechanical operations may be repeated, while removing as much of the solvent as is necessary to produce an impoverished atmosphere to render it non-explosive. The impoverishment of the atmosphere may be controlled by regulating the action of the condenser 61, or if insufficient solvent remains to justify the recovery thereof, the bottom door 55 may be opened 20 and the fans 65 allowed to circulate air through the chamber thereby reducing the percentage of combustible vapor in the atmosphere below the lower explosive limit. For this purpose the casing 99 of the fans 25 57 may be conveniently made removable, or openings, 100, opposite the fans 64 may be provided. To regulate the temperature in either chamber heating coils 101, 101' are provided which are protected from fragments of celluloid dropping on them by a cover plate 102, 102'.

Referring to Figs. 4, 5 and 6 showing an apparatus adapted for the treatment of artificial leather and the like, 1 and 2 represent 30 end walls of the apparatus, and 3, 4, 5 and 6 side walls, respectively, of a pair of drying-chambers. 7 and 8 represent the bottom and top, respectively, of the lower chamber, and 9 and 10, the bottom and top 35 of the upper chamber. Partitions 11 in the lower, and 12 in the upper chamber, divide them into drying-chambers proper 13 and 14, and condenser chambers 15 and 16, each of the latter containing respectively, condensers 17 and 18 supplied with a cooling fluid at a regulated rate or temperature. 40 21, 22, 23 and 24 represent baffles in the drying chambers. In each of the drying-chambers 13 and 14 is located heating coils 19 and 20, respectively, and the upper chamber has an extension provided with a window 45 35 and a supply-pipe 26 leading from container 27 to supply jelly therefrom with which the web of goods 28 is to be treated.

This web is suitably fed to the machine from 65 the magazine roll 29 passing over a gripping roller 30 and retarding roller 31 into the extension through the slot 32. In this extension the web receives the jelly 33 passing first over the supporting roller 34, then 70 under the doctor-knife 35 and over the supporting roller 36. Any excess of jelly falls from the edges of the web into the trough 37 and is arranged to be withdrawn from the machine in any suitable manner. In this 75 extension a considerable quantity of solvent is evaporated from the jelly and the vapor passes into the top of the drying-chamber 14. From the extension the web passes into the upper drying-chamber between suitable baffles 80 22, 23, 24 which direct the current of drying medium across its surface, and passing over supporting rollers 38 and 39 the web is exposed to the heating drying medium so that it loses most of its solvent and maintains a 85 high degree of saturation of the drying medium which is rendered possible by the elevated temperature produced by means of heating coils 20, and the only partially, and far from completed condensation produced 90 by the cooling liquid flowing in the condensing pipes 18 at a moderately elevated temperature. From this chamber in which the medium is maintained in a state of high saturation, the web, freed from most of its 95 solvent, passes through a tight slot 40 into the lower chamber 13 where the remaining portion of the solvent is to be evaporated, condensed and recovered. In this lower chamber the web passes over the feed roller 100 41 and gripping roller 42 and piles up in folds 43 on the belt, conveyer 44, being exposed for a long time in this chamber to the action of the drying medium which may be as hot as previously, but which contains a 105 much smaller proportion of solvent vapor, which is more completely removed from the chamber, for instance, as by circulating refrigerated brine in the condensing coil 17 or by using cold water. This cold water 110 becoming warmer may be used in the condenser 18 of the high saturation chamber. After becoming dry in the lower chamber the web passes between rollers 45 and around the tension roller 46, and is wound up on 115 the magazine roll 47. It will be seen that by this means the solvent is recovered in two stages, in the first the goods being dried in an atmosphere so highly saturated with a combustible vapor as to be non-explosive 120 and, in the second, in an atmosphere so largely depleted of combustible vapor as to render it non-explosive.

It will be apparent that the use of mixed solvents produces mixed vapors, each constituent of which will, according to the natural laws, have its independent vapor pressure, and it is therefore possible to main-

tain the desired conditions above outlined, at a much lower temperature where mixed or complex solvents are used.

At a temperature of 20° C. the vapor tension of ethyl alcohol is 45 m. m., corresponding to the production of about a 6% vapor. If however, both methyl alcohol and ethyl alcohol are present, the methyl alcohol will have an independent vapor tension of about 10 65 m. m., corresponding to 8½% vapor. This makes a total of vapor tension of 110 m. m., corresponding to the production of about 14½% vapor. While this mixture might not be entirely safe it will be apparent 15 that if benzol having a vapor tension at 20° C., of 76 m. m., be also a constituent of the mixture, it will tend to contribute 76 m. m., to the partial pressure, and make the total partial pressure of all 20 vapors 186 m. m., corresponding to approximately 24½% of combustible vapor. These partial pressures are only approximate, being individually influenced by the material mixed with the liquid or by other liquid being 25 simultaneously evaporated or condensed, but they serve to illustrate this one valuable feature and aid in carrying out my invention. It will also be apparent that during the second stage of the operation the impoverishment 30 of the combustible vapor may be obtained in several different ways, either one of which may be used in conjunction with the initial treatment.

35

First: The impoverishment may be brought about by admitting such an excess of air to the drying chamber as to increase the proportion of nitrogen and oxygen, and 40 decrease the proportion of combustible vapor below that point at which the propagation of explosion is possible.

Second: The vapor of a non-combustible solvent such as carbon tetrachlorid or a non-combustible fixed gas such as nitrogen, may 45 be made a constituent of the mixture or drying medium to such a degree that the explosive wave will no longer propagate therein.

Third: By adsorption or condensation of 50 the combustible constituents of the drying medium they may be so far removed without affecting the composition of the fixed gases that explosive propagation is no longer possible.

Fourth: The total pressure of all the vapors and gases may be so far reduced that propagation of the explosion wave is no longer possible.

Fifth: By substitution in place of constituents having a relatively low lower limit of explosibility, a constituent likewise explosive but having a relatively high lower limit of explosibility.

The lower explosive limit of percentage

of certain vapors is sufficiently elevated that 65 any one of these methods may be chosen which proves most convenient. However, the explosive limits of percentage of other vapors are so low that a choice of the above methods, or a combination of them, may be 70 preferable. But in general, any one of the above methods is applicable in connection with the first stage of the process.

While the treatment of excessively enriched vapors has been described as the first 75 stage of the process, and treatment of excessively impoverished vapors has been described as the second stage, I do not desire to be limited to a process in which these two stages are thus successive in time. The 80 order may be reversed, or they may be carried out in any other desired manner, although under certain circumstances it is advantageous to carry out, first, the stage mentioned as the first stage. Any suitable 85 and well known apparatus may be used for carrying out my invention.

Although I have described my improvements in great detail, and have specifically mentioned certain temperatures, pressures 90 and other conditions which may be desirable in certain particular cases, nevertheless I do not desire to be limited to such details nor to such particular conditions except as clearly specified in the appended claims, 95 since many changes and modifications may well be made without departing from the spirit and scope of my invention.

Having fully described my improvements, what I claim as new and desire to secure by 100 Letters Patent, is:

1. The method of handling combustible vapors evolving from material during the course of manufacture, which consists in treating the material in two stages, in the 105 first stage maintaining the percentage of volatilized vapor in the medium surrounding the material so great that the medium is non-explosive, and in the second stage maintaining the percentage of volatilized 110 vapor in the surrounding medium so small that the medium is non-explosive.

2. The process of handling combustible vapors which consists in carrying out the process in two stages, in one stage maintaining the vapors in a condition of excessive enrichment to render them non-explosive, and in the other stage maintaining them in a condition of excessive impoverishment to 115 render them non-explosive.

3. The process of recovering solvents evolved from material in drying operations which consists in condensing the solvents in two stages, in the first condensing only so much of the solvents as to maintain such a 125 comparatively large percentage of solvent vapor in the medium surrounding the material as to render the medium non-explo-

sive, and in the second condensing and removing so much of the solvent vapor as to maintain such a comparatively small percentage of solvent vapor in the surrounding medium as to render the medium non-explosive.

4. The process of handling combustible vapors evolving from material in drying operations which consists in treating drying 10 in two stages, in one maintaining the drying medium in a non-explosive condition due to excess of combustible gas or vapor, and in the other stage maintaining the drying medium in a non-explosive condition due to 16 excess of non-combustible gas or vapor.

5. The method of handling combustible gases evolving from material in drying operations and the like, which consist in handling them in two stages, in one stage adjusting the temperature, pressure, rate of evolution and removal of gases such that the ratio of combustible gas to oxygen is excessive so that the propagation of explosions is prevented, and in the second stage 25 adjusting the temperature, pressure, rate of evolution and removal of gases such that the ratio of air to combustible gas is so great that explosion is prevented.

6. The method of handling combustible 30 gases and the like evolving from material in drying operations and the like which consists in adjusting the temperature, pressure, rate of evolution and removal of combustible gases such that the percentage of combustible gases in the surrounding medium is beyond the limit at which, under the particular conditions of temperature and pressure, an explosion can propagate.

7. The process of recovering solvents 40 evolved in the manufacture of material which consist in carrying out the recovery in two stages, in the first stage adjusting the temperature, rate of vapor evolution and removal of vapor such that the ratio of combustible vapor to oxygen in the surrounding medium is beyond the limit at which under the particular conditions of temperature and pressure an explosion can propagate.

50 8. In the manufacture of celluloid and similar material softened with solvents, the improved process which consists in first subjecting the material to a medium surcharged beyond the explosive limit with combustible vapor and heating the material, and further subjecting it to a medium too impoverished for the propagation of an explosive wave.

9. The method of handling a mixture of 60 combustible gases mixed with non combustible gas in drying operations and the like, in which combustible gas is evolved, which consists in suitably arranging the temperature, pressure, rate of evolution, and re-

moval of combustible gas in such a manner 65 that the ratio of combustible gases to non-combustible gas is increased beyond the limit at which, under the particular conditions of temperature and pressure, an explosion can propagate.

70 10. The process of drying out and recovering solvents forming combustible vapors from material which consists in subjecting the material to be dried first to a drying medium containing so large a percentage of solvent vapor as to render the medium non-explosive at the prevailing temperature and pressure, and then subjecting the material to a drying medium having such a small percentage of said combustible solvent vapor as to render the medium non-explosive at the then prevailing temperature and pressure.

80 11. The method of handling combustible gases mixed with non combustible gas in 85 drying operations and the like, in which combustible gas is evolved, which consists in carrying out the treatment in two stages, in one stage suitably arranging the temperature, pressure, rate of evolution, and 90 removal of combustible gas in such a manner that the ratio of combustible gases to non-combustible gas is increased beyond the limit at which, under the particular conditions of temperature and pressure, an explosion can propagate, and in the other stage suitably arranging the temperature, pressure, rate of evolution and removal of combustible gas in such manner that the ratio of combustible gases to non-combustible 95 gas is decreased below the limit at which, under the particular conditions of temperature and pressure present, an explosion can propagate.

100 12. The process of handling combustible 105 vapors in drying operations and the like which consists in subjecting the material to be dried first to a drying medium containing so large a percentage of combustible vapor as to render the medium non-explosive at 110 the prevailing temperature and pressure, and then subjecting the material to a drying medium having the percentage of readily explosive vapor so far reduced by the presence of other constituents that the 115 explosive wave can no longer propagate.

13. The improved method of treating volatile constituents in the manufacture of celluloid and other bodies softened with solvents, which consists in first manipulating the bodies in an atmosphere non-explosive by dilution of oxygen, and second, heating the bodies and completing the treatment in an atmosphere rendered non-explosive by dilution of the combustible constituent.

120 14. The improved method of treating combustible gas, vapors or the like, in drying, and similar processes which consists in car-

rying out the treatment, first in an atmosphere non-explosive by dilution of the oxygen, and second in an atmosphere rendered non-explosive by dilution of the combustible constituent.

5 In testimony whereof, I have signed my

name to this specification, in the presence of two subscribing witnesses.

WILLIAM M. GROSVENOR.

Witnesses:

GORHAM CROSLEY,
EDWIN SEGER.

It is hereby certified that in Letters Patent No. 1,143,623, granted June 22, 1915, upon the application of William M. Grosvenor, of Ridgewood, New Jersey, for an improvement in "Handling and Treating Combustible Gases and Vapors," an error appears in the printed specification requiring correction as follows: Page 1, line 33, for the article "The" read *One*; and that the said Letters Patent should be read with this correction therein that the same may conform to the record of the case in the Patent Office.

Signed and sealed this 27th day of July, A. D., 1915.

[SEAL.]

R. F. WHITEHEAD,

Acting Commissioner of Patents.
